DEVICE FOR REMOVING AND REPLACING
PISTON RINGSHarry W. Kulp, Lancaster, Pa., assignor to K-D
Manufacturing Company, a corporation of
Pennsylvania

Application December 17, 1937, Serial No. 180,438

7 Claims. (Cl. 29—86.4)

My invention relates to a device for removing and replacing piston rings.

The objects of my invention are, to provide a tool having end aligning clamping means for the piston ring and independently operable expanding means permanently associated with said clamping means, said end clamping means holding the ring in such a position that it may be positively engaged and expanded by said expanding means; to provide said tool with end aligning clamping means which, after initially engaging the piston ring, remains motionless and permits the ends of the ring to slide apart therethrough during the expanding operation and at the same time holds said ends in alignment in a common plane; to provide, in connection with each end aligning clamp, a common means for maintaining the oppositely disposed members thereof in registering relation and positioning the piston ring in proper operative relation to the expanding means; and to provide a very simple efficient tool of the above nature which is strong and durable in operation, is economical to manufacture, and may be composed of sheet metal parts and manufactured by well known sheet metal stamping operations.

In this application I show and describe only the preferred embodiment of my invention simply by way of illustration of the practice of my invention as by law required. However, I realize that my invention is capable of other and different embodiments and that the details thereof may be modified in various ways, all without departing from my said invention. Therefore the drawing and description herein are to be considered merely as illustrative and not as exclusive.

In the accompanying drawing:

Figure 1 represents a top plan of my improved tool as applied to a piston ring, the expanding means being in inoperative position;

Figure 2, a side elevation;

Figure 3, a front elevation;

Figure 4, a section on the line 4—4 of Figure 1 looking in the direction of the arrows, the top plate 2 being omitted;

Figure 5, a top plan of the tool showing the expanding means in operation on a piston ring, the upper plate 2 of the tool being removed and the connecting spring 3 and guide posts 5 being shown in section; and

Figure 6, a section on the line 6—6 of Figure 1 looking in the direction of the arrows.

The tool of the present invention comprises a piston ring end aligning clamp and independ-

ently operable expanding means permanently associated with said clamp.

The end aligning clamp comprises a preferably heavy sheet metal lower or base plate or member 1, which for the purposes of this description shall be considered to be immovable, a preferably heavy sheet metal plate or upper member 2 disposed in vertical registering relation to plate 1 and which, for the purposes of this description, shall be considered to be relatively movable with respect to said plate 1, and any suitable means, such as a spring 3, resiliently connecting said plate 2 to said plate 1, and urging one edge of said plate 2 towards the opposed registering edge of said plate 1.

A pair of spaced horizontally aligned, preferably upwardly offset jaw members, each said member 4 preferably having a vertical guide post 5 rigidly attached to the upper face thereof, projects from the forward edge of plate 1, the rear portion of said plate 1 tapering back to form a handle 6 which preferably has a hole 6^a formed therein to facilitate gripping the same or hanging the same on a hook etc. Preferably an arcuate slot 16 is formed in the medial portion of said plate 1.

A pair of spaced horizontally aligned, preferably downwardly offset jaw members 4', each of said members having a hole 5' formed therein to receive the respective guide posts 5 of members 4 for vertical movement thereon project from the forward edge of plate 2 in vertical registry with the opposed members 4 of plate 1, the rear portion of said plate 2 tapering back to form a handle 6' preferably having a hole 6^b formed therein, said handle being disposed substantially in vertical registry with the corresponding handle 6 of the lower plate 1.

Any suitable means may be used to connect plate 2 in vertical registry to plate 1, in such a manner that the jaw members 4 of said plate 2 are resiliently urged downward toward the respective opposing members 4 of plate 1 but may be separated therefrom to permit the end portions of a piston ring A to be inserted therebetween.

In the embodiment shown, a preferably W-shaped spring 3, of flat cross-sectional material, has one end connected to each plate 1 and 2 by any suitable means, such as rivets 7, to perform the above described functions. The use of such a W-shaped spring 3 permits the jaw members 4' to be moved upward with respect to their respective opposing members 4 by downward pressure on the handle 6' of plate 2.

Preferably, in the assembled relation of plates 55

1 and 2, guide posts 5 are so positioned that when a piston ring A is engaged by each of the respective pairs of opposed members 4-4' the outer circumference of each end portion of the ring 5 A rests against one of the guide posts 5 and the ends of the said jaw members 4 and 4' lie flush with the inside of the ring A, said guide posts 5 passing through holes 5' in the upper jaw members 4', which are adapted to move vertically on, 10 and be held in vertical registry by, said guide posts 5.

The expanding means may consist of any independently operable means permanently associated with one of the plates 1 or 2 which may be adapted to spread apart the ends of a piston ring engaged by the members 4 and 4' of the piston ring end aligning clamp.

Preferably the expanding means comprises a pair of opposed non-crossing preferably channelled members 8 and 8' preferably of U-shape in cross-section. Each of said members 8 and 8' preferably is medially pivoted to plate 2 by suitable means such as pivot pins 12. Portions of each of said members 8 and 8' extend rearwardly from said pivot pins 12 to form handles 11, while shank portions 9 extend forwardly from said pivot pins 12, each said shank portion 9 having a preferably integral vertically disposed flat expander jaw member 10 mounted on the 30 forward end thereof.

The oppositely disposed expander jaw members 10 are preferably held together in inoperative position by some resilient means, such as a coil spring 13 having its ends connected to oppositely disposed portions of the respective shank portions 9.

Preferably the members 8 and 8' are provided on their lower sides with laterally inwardly extending lugs 14 and 14' respectively which project towards each other and overlap at their tips, a common vertical guide pin 15 is snugly fitted into a hole in the tip of lug 14 and extends through guide slots 16 and 17 of plate 1 and lug 14' respectively, the sides of each said slot 16 and 17 slidably contacting, and acting as guides for, said pin 15. Preferably the ends of pivot pin 15 are riveted over.

It is to be noted that slot 18 is in the form of an arc having at its center of curvature the pivot pin 12 of member 8, said slot 16 together with slot 17 serving at all times to maintain the expander jaw members 10 equidistant from, and on opposite sides, of the longitudinal center line of plate 1, preventing any angular movement between plate 1 and the expanding means as a whole.

In the preferred embodiment of my invention the expanding means is preferably disposed between the lower and upper plates 1 and 2, being 60 preferably permanently attached to the upper face of plate 1 with the expander jaw members 10 projecting to the front of said plates 1 and 2 and having their centers substantially in horizontal alignment with jaw members 4 and 4' of the end 65 aligning clamps, said members 10 extending in a vertical direction for a substantial distance above and below the planes of the respective upper and lower faces of a piston ring A engaged by members 4 and 4' to insure a positive engagement of the abutting ends of said piston ring A by said members 10 regardless of the shape of said piston ring ends.

It is to be noted that the forward edges of plates 75 1 and 2 are curved inwardly to afford the oper-

ator a clear view of jaw members 10 and the ends of the piston ring A engaged thereby.

In operation the clamp jaw members 4 and 4' are separated by downward pressure on handle 6' to receive the end portions of a piston ring A in such a manner that the expander jaw members 10 lie between the abutting ends of the ring A, and the outer circumference of the ring A near each said end portion rests against, and is positioned by, one of the guide posts 5, as in Figure 1 of the drawing. Upon releasing the handle 6' the jaw members 4 and 4' resiliently engage the end portions of ring A and hold them in aligned position. The jaws 10 are then caused to engage and expand or spread apart the ends of the ring A by means of pressure applied to their handles 11, as in Figure 5, thereby causing the ring ends to spread laterally outward through the jaw members 4 and 4' and against the posts 5 while being held by the same in proper operative position with respect to the expander jaws 10. When sufficiently expanded, the ring A may be applied by slipping it over the piston and allowing it to contract in its groove. Similarly ring A may be expanded to remove the same.

The construction of the clamp jaws 4 and 4' whereby they do not project beyond the inner circumference of the piston ring permits them to clear the piston when the ring is to be removed from or applied to the same.

I claim:

1. A piston ring removing and applying tool comprising a pair of opposed registering sheet metal plates, each said plate having a pair of forwardly projecting spaced aligned jaw members and a rearwardly extending handle portion said jaw members of each said plate being offset towards the respective opposed members of the other plate, a pair of vertical guide posts rigidly attached to the respective jaw members of one plate and passing through holes formed in the respective opposed members of the other plate and means serving to connect said plates and resiliently urge the respective opposed jaw members thereof towards each other, in combination with expanding means disposed between said plates, said expanding means comprising a pair of opposed non-crossing levers respectively pivoted at their medial portions to one of said plates, each said lever having a handle extending rearwardly from its medial portion and a shank extending forwardly from said portion, an expander jaw mounted at the forward end of each shank means resiliently urging said expander jaws together, and a pair of laterally inwardly extending overlapping lugs respectively mounted on the lower side of each said lever, a common vertical guide pin rigidly attached to one of said lugs and extending through guide slots in the other of said lugs and one of said plates respectively to prevent angular movement between said lower plate and said expanding means.

2. A piston ring removing and applying tool comprising a pair of opposed registering sheet metal plates, each said plate having a pair of forwardly projecting spaced aligned jaw members and a rearwardly extending handle portion, said jaw members of each said plate being offset towards the respective opposed members of the other plate, a pair of vertical guide posts rigidly attached to the respective jaw members of one plate and passing through holes formed in the respective opposed members of the other plate and means serving to connect said plates and resiliently urge the respective opposed jaw mem-

thereof towards each other, in combination with expanding means comprising a pair of opposed non-crossing levers resiliently pivoted at their medial portions to one of said plates, each said lever having a handle extending rearwardly from its medial portion and a shank extending forwardly from said medial portion, an expander jaw mounted at the forward end of each shank, and a pair of laterally inwardly extending overlapping lugs respectively mounted on the lower side of each said lever, a common vertical guide pin rigidly attached to one of said lugs and extending through guide slots in the other of said lugs and the lower plate respectively.

5. A piston ring removing and applying tool comprising a pair of opposed registering rigid plates, each said plate having a pair of forwardly projecting spaced aligned jaw members and a rearwardly extending handle portion, a pair of vertical guide posts rigidly attached to the respective jaw members of one plate and passing through holes formed in the respective opposed members of the other plate, and means serving to connect said plates and resiliently urge the respective opposed jaw members thereof towards each other, in combination with expanding means comprising a pair of opposed levers respectively pivoted at their medial portions to one of said plates, each said lever having a handle extending rearwardly from its medial portion and a shank extending forwardly from said portion, an expander jaw mounted at the forward end of each shank, and means for preventing relative angular movement between said plates and said expanding means.

10. A piston ring removing and applying tool comprising a pair of opposed registering rigid plates, each said plate having a pair of forwardly projecting spaced aligned jaw members and a rearwardly extending handle portion, a pair of vertical guide posts rigidly attached to the respective jaw members of one plate and passing through holes formed in the respective opposed members of the other plate, and means serving to connect said plates and resiliently urge the respective opposed jaw members thereof towards each other, in combination with expanding means comprising a pair of opposed levers respectively pivoted at their medial portions to one of said plates, each said lever having a handle extending rearwardly from its medial portion and a shank extending forwardly from said portion, an expander jaw mounted at the forward end of each shank, and means for preventing relative angular movement between said plates and said expanding means.

15. A piston ring removing and applying tool comprising a pair of opposed registering rigid plates, each said plate having a pair of forwardly projecting spaced aligned jaw members and a rearwardly extending handle portion, a pair of vertical guide posts rigidly attached to the respective jaw members of one plate and passing through holes formed in the respective opposed members of the other plate, and means serving to connect said plates and resiliently urge the respective opposed jaw members thereof towards each other, in combination with expanding means comprising a pair of opposed levers respectively pivoted at their medial portions to one of said plates, each said lever having a handle extending rearwardly from its medial portion and a shank extending forwardly from said portion, an expander jaw mounted at the forward end of each shank, and means for preventing relative angular movement between said plates and said expanding means.

20. A piston ring removing and applying tool comprising a pair of opposed registering rigid plates, each said plate having a pair of forwardly projecting spaced aligned jaw members and a rearwardly extending handle portion, a pair of vertical guide posts rigidly attached to the respective jaw members of one plate and passing through holes formed in the respective opposed members of the other plate, and means serving to connect said plates and resiliently urge the respective opposed jaw members thereof towards each other, in combination with expanding means comprising a pair of opposed levers respectively pivoted at their medial portions to one of said plates, each said lever having a handle extending rearwardly from its medial portion and a shank extending forwardly from said portion, an expander jaw mounted at the forward end of each shank, and means for preventing relative angular movement between said plates and said expanding means.

25. A piston ring removing and applying tool comprising a pair of opposed registering rigid plates, each said plate having a pair of forwardly projecting spaced aligned jaw members and a rearwardly extending handle portion, a pair of vertical guide posts rigidly attached to the respective jaw members of one plate and passing through holes formed in the respective opposed members of the other plate, and means serving to connect said plates and resiliently urge the respective opposed jaw members thereof towards each other, in combination with expanding means comprising a pair of opposed levers respectively pivoted at their medial portions to one of said plates, each said lever having a handle extending rearwardly from its medial portion and a shank extending forwardly from said portion, an expander jaw mounted at the forward end of each shank, and means for preventing relative angular movement between said plates and said expanding means.

30. A piston ring removing and applying tool comprising a pair of opposed registering rigid plates, each said plate having a pair of forwardly projecting spaced aligned jaw members and a rearwardly extending handle portion, a pair of vertical guide posts rigidly attached to the respective jaw members of one plate and passing through holes formed in the respective opposed members of the other plate, and means serving to connect said plates and resiliently urge the respective opposed jaw members thereof towards each other, in combination with expanding means comprising a pair of opposed levers respectively pivoted at their medial portions to one of said plates, each said lever having a handle extending rearwardly from its medial portion and a shank extending forwardly from said portion, an expander jaw mounted at the forward end of each shank, and means for preventing relative angular movement between said plates and said expanding means.

35. A piston ring removing and applying tool comprising a pair of opposed registering rigid plates, each said plate having a pair of forwardly projecting spaced aligned jaw members and a rearwardly extending handle portion, a pair of vertical guide posts rigidly attached to the respective jaw members of one plate and passing through holes formed in the respective opposed members of the other plate, and means serving to connect said plates and resiliently urge the respective opposed jaw members thereof towards each other, in combination with expanding means comprising a pair of opposed levers respectively pivoted at their medial portions to one of said plates, each said lever having a handle extending rearwardly from its medial portion and a shank extending forwardly from said portion, an expander jaw mounted at the forward end of each shank, and means for preventing relative angular movement between said plates and said expanding means.

40. A piston ring removing and applying tool comprising a pair of opposed registering rigid plates, each said plate having a pair of forwardly projecting spaced aligned jaw members and a rearwardly extending handle portion, a pair of vertical guide posts rigidly attached to the respective jaw members of one plate and passing through holes formed in the respective opposed members of the other plate, and means serving to connect said plates and resiliently urge the respective opposed jaw members thereof towards each other, in combination with expanding means comprising a pair of opposed levers respectively pivoted at their medial portions to one of said plates, each said lever having a handle extending rearwardly from its medial portion and a shank extending forwardly from said portion, an expander jaw mounted at the forward end of each shank, and means for preventing relative angular movement between said plates and said expanding means.

posed jaw members of said plates towards each other, in combination with independently operable expanding means mounted on one of said plates, said means comprising a pair of jaws in alignment with said aligned jaw members, and means for moving one of said jaws away from the other.

5. A piston ring removing and applying tool comprising a clamping means consisting of a pair of opposed rigid plates, a pair of aligned jaw members projecting from each said plate in substantial registry with the respective jaw members of the other plate, and means resiliently urging the respective opposed jaw members of said plates towards each other, in combination with independent operable expanding means permanently associated with said clamping means.

6. A piston ring removing and applying tool comprising two sheet metal plates rockably connected to form a clamp having two pairs of spaced aligned jaws, said plates being spaced apart between said pairs of jaws to form an aperture, and a plier type expander having its jaws projecting through the aperture between said plates for relative movement in a plane at right angles to the movement of said clamping jaws.

7. A piston ring removing and applying tool comprising a pair of members connected in registering relationship for relative rocking movement, and having clamping portions carried by said respective members to be moved toward and away from each other during rocking movement of said members, in combination with independently operable expanding means mounted on one of said members, said means projecting between said opposed clamping portions and being disposed for movement in a direction at right angles to the direction of rocking movement of said members to engage and spread the ends of a piston ring held between said clamping portions.

HARRY W. KULP.
